UNITED STATES PATENT OFFICE.

JOSEPH A. KENNEDY, OF PAWTUCKET, RHODE ISLAND, ASSIGNOR TO CHERNACK MANUFACTURING COMPANY, OF PROVIDENCE, RHODE ISLAND, A CORPORATION OF RHODE ISLAND.

CIRCULAR LOOM.

1,327,676.

Specification of Letters Patent. Patented Jan. 13, 1920.

Application filed February 2, 1916. Serial No. 75,865.

To all whom it may concern:

Be it known that I, JOSEPH A. KENNEDY, a citizen of the United States, residing at Pawtucket, in the county of Providence and State of Rhode Island, have invented new and useful Improvements in Circular Looms, of which the following is a specification.

The present invention relates to looms for circular weaving, adapted to produce such articles, among others, as tubes, conduits, seamless sheathing for ropes, etc. Looms of the sort to which the invention relates are adapted to employ any of the materials which may be used for weaving. The type of loom to which more particularly the invention relates is that of the Chernack loom shown in patents of Abraham Chernack No. 920,728 granted May 4, 1909, and No. 1,088,061 granted February 24, 1914, respectively. The objects of the invention are to effect certain improvements in the loom by which improved results are obtained in the way of simplicity of construction, efficiency of operation, and more rapid production, all as more fully appears in the following specification and claims.

In the drawings,

Figure 1 is a vertical central section of a loom embodying many of the features in which the present invention consists.

Fig. 2 is a plan view, with parts broken away, of the loom shown in Fig. 1.

Fig. 3 is a detail view partly in section showing the warp thread take-up devices and stop motions and a part of the shuttle thread stop motion.

Fig. 4 is an elevation of the stop motions shown in Fig. 3.

Fig. 5 is an elevation of one of the guides for the heddles or slides.

Fig. 6 is a detail elevation of the lower end of one such guide and a fragment of the connecting ring therefor.

Fig. 7 is an elevation of one of the heddles or slides.

Fig. 8 represents two of the antifriction rolls carried by the heddles or slides.

Fig. 9 is a view similar to Fig. 3 showing a modification in the construction of the heddles or slides of the loom.

Fig. 10 is a front elevation of two of the adjacent heddles represented in Fig. 9.

Fig. 11 is a plan view of a section of the

loom showing three of the adjacent heddles embodying the modification shown in Figs. 9 and 10.

Fig. 12 is a front elevation of the warp thread take-ups associated with the heddles represented in Figs. 9, 10, and 11.

Fig. 13 is a diagrammatic view showing a development of the interior of the circular frame, indicating the operating cams, the driving plates of the shuttles, and the alternately arranged guides and heddles or slides.

Fig. 14 is a sectional view showing in detail a form of main clutch for transmitting driving power to the loom.

Reference is first made to Figs. 1 and 2 for a comprehensive view of the loom as a whole. 25 represents a bed or table supported upon legs 26 which are adapted to rest on the floor of the mill. Resting solidly on the table is a cylindrical casing 27 having a base 28 and a central column 29, the latter furnishing a bearing for the rotary cam wheel 30 which has a hub 31 fitting the column 29 and carries a cylindrical outer cam 32 and a concentric cylindrical inner cam 33. These cams are arranged with an annular space between them

into which project the lower ends of the heddles or slides 34, 35, and of guides 73 (later described) between the slides. Alternate slides, which are designated by the character 34 are operated by a groove 36 in the cam 32 (see also Fig. 13), while the intermediate slides designated 35, are operated by a groove 37 in the cam 33. Secured to the bottom of the rotary cam wheel is an annular spur gear 37a which is driven by a gear 38 on an upright shaft 39 which has a bearing in the machine base and is driven by bevel gearing 40, 41 from a main shaft 42,

on which a pulley 43 is loosely mounted and a clutch 44 is fixed.

One or a number of shuttles 45 travel circularly about the axis of the casing 27, and carry bobbins 46 of shuttle thread or filling, which is interwoven with warp threads 100 about a core or mandrel 47 secured to the column 29, as clearly shown in Fig. 1.

The warp threads 48 pass from reels mounted on a rack (not shown) beside the loom, through a guiding eye 49, fixed in any convenient location, whence they are distributed to take-up mechanisms consisting of links 50 and 51, spaced equally apart

entirely around the frame of the loom. All of the take-up mechanisms are alike. The link 50 of each is pivoted upon lugs projecting from a ring 52 which forms part 5 of an upper frame secured to the casing 27, said upper frame having a base ring 53, a top ring 54, and posts or webs 55 connecting all three rings together. Secured to the top ring is a flange or shield 56 which over- 10 lies the sliding heddles and their guides.

A crossbar 57 rests on the shield 56 and is secured to the ring 54. It crosses the center of the frame and supports a guide 58 through which the tubular web 59 woven on 15 the machine passes. The lower end of the guide 58 is tapered and terminates a short distance above a tapered or reduced part of the mandrel, leaving open a comparatively narrow zone at the weaving point. 20 The tubular web is passed over a large wheel 60 which is rotated at uniform speed and exerts a constant tension on the web. This wheel is mounted in a bracket 61 secured to the top of the frame. It carries a 25 gear element 62 to which the impulse of rotation is applied by a worm 63 driven by gearing 64, 65, 66, 67, 68, 69, and a worm 70, the latter being on an upright shaft 71 to which is keyed a gear 72 meshing with the 30 gear 38 previously described. Thus the take-up is driven in synchronism with the loom at a rate which, by adjustment of the gear train, may be made exactly proportional to the rate of weaving.

35 Between adjacent heddles are arranged the fixed guide bars 73 which are fastened to the rings 54 and 53 of the upper frame by means of bolts 74, 75, and project down into the space between the cams 32 and 33, where 40 their lower ends are connected to a ring 75^a. Said guide bars also have on their inner faces projections 76, 77 which collectively form a dovetail guideway or track surrounding the axis of the loom, on which the 45 shuttles travel. One of the guides is shown in detail in Fig. 5, and in association with the shuttle, heddles, and take-ups in Fig. 3. The guides have channels 731 running lengthwise in their opposite sides, which 50 open into the spaces between adjacent guides, and in which travel longitudinal ribs 341 on the opposite sides of the heddles or slides.

An important detail of the machine, in 55 which one of the features of my invention resides is the connecting ring 75^a and the mode in which the guide bars 73 are associated with said ring. It is apparent from Fig. 1 that these bars extend to a considerable 60 distance from their lower point of anchorage upon the rigid frame ring 53 into the space between the cams. Unless they were anchored in some efficient manner these projecting ends of the guides would be deflected or sprung aside in consequence of the 65

severe side thrust applied to them through the slides or heddles, which are pressed against laterally by inclined cams, as fully described in the passage of this specification immediately following; said cams serving 70 to shift the heddles endwise against considerable resistance, and thereby exerting a substantial component of lateral force through the heddles against the guide bars. At the same time the cams tend to twist 75 the heddles about their longitudinal axes by reason of the fact that the rolls (presently described) on which the cams act project laterally from the heddles, as appears both from Fig. 1 and Fig. 7. This twisting action 80 is transmitted to the bars, tending to twist the latter. The connecting ring 75^a previously mentioned completely surrounds the axis of the loom, lying in the annular space between the inner and outer cams, and is 85 engaged with the lower ends of all of the guide bars 73. Said guide bars enter shallow grooves or notches 75^b in the upper face of the ring, and in addition have dowel pins 75^c entering sockets in the ring, substantially as 90 shown in Fig. 6. The side walls of these notches fit closely against the sides of the bars, wherefore the notches and pins co-act in preventing deflection of the lower ends of the bar, and the sides of the notches 95 further serve to prevent twisting of the bar. The notches still perform both these functions even in case the dowel pins should become loosened by the jarring of the loom and fall through the socket holes in the 100 ring. Said ring is secured at two or more points to the adjacent guide bars by screws, which hold it in place and prevent it from falling away from the bars.

The sliding heddles serve the function of 105 propelling the shuttles as well as of guiding the warp threads, and to that end each heddle has an inwardly directed tubular projection 78 which provides the eye for the warp thread and also supports an anti- 110 friction roll 79 bearing on the edge of the cam-like base plate 80 of the shuttle. Alternate heddles bear on the upper edge of said plate and the intermediate heddles on the bottom edge thereof, as shown in the development view Fig. 13.

The latter view illustrates in full lines the groove 36 of the outer cam 32 and in dotted lines the groove 37 of the inner cam 33. These grooves in the two cams are similar, 115 but oppositely arranged, so that each high point of one is opposite to a low point of the other, and the inclines connecting high and low points of the two cam grooves cross one another, in essentially the same manner, and with essentially the same effect, as described in the Chernack patents above referred to. There are two antifriction rolls 81, 82 upon each of the sliding heddles, such rolls being shown in Fig. 13 and indicated 120

by dotted lines in Fig. 7. The roll 81 engages the upper surface of the cam groove and roll 82 the lower surface, these rolls being independent of one another and separated sufficiently to turn out of contact with one another. The two rolls constitute anti-friction means carried by the sliding heddle which may be in contact with both surfaces of the cam groove at the same time, such means including two members capable of rotating independently of one another, and therefore being adapted to rotate in opposite directions and to make rolling contact with the cam surfaces wherewith they are respectively engaged. The cams may thus operate the heddles without backlash and without sliding friction.

The projections 76 and 77 on the guide bars 73, which form the track for the shuttle, do not actually support the shuttles, but instead the latter are supported wholly by the antifriction rolls 79 so that in effect the shuttles float clear of the track, and the latter merely serves as a guide to determine the path of the shuttles. The track elements 76, 77 instead of being dovetailed or inclined as in the patents referred to are square, as shown in Figs. 3 and 5 and the base plate of the shuttle is equipped with flanged gibbs 83 embracing the track elements, as shown in Fig. 3. The latter figures also show the floating relation of the shuttle to the track.

Further explanation of the warp take-up motion will now be given with reference to Figs. 3 and 4. It will be seen from these figures that the link 50 of each take-up is pivoted to lugs 84 which are secured to the fixed ring 52 and that the link 51 is jointed by a pivot pin 85 at one end to the link 50 and by a pivot 86 at the other end to a head 87 which is fixed to the adjacent heddle. At the knuckle of the links, that is the pivot 85 there is provided a roll 88 over which the warp thread passes. For practical convenience the links are made double, that is each being composed of two flat bars placed parallel to one another, as appears from Fig. 4, the roll 88 being placed between the duplicate linkages which form the one take-up. The warp thread in passing to each take-up extends back of a stud 89 and in front of a stud 90, said studs being fixed in the lugs 84, and thence between the bars which form the link 50, around the roll 88, and between the two bars of the link 51 to the eye 78, whence it passes directly to the weaving point. The object of the take-up is, of course, to keep the warp thread under uniform tension as the heddles rise and descend. This object is accomplished by the mechanism here described for the reason that the distance from the stud or pin 89 to the weaving point via the roll 88 and the eye 78 is always the same whatever may be the position of the heddle and the obliquity of the

line from its eye to the weaving point. The distance from the weaving point to the eye is of course least when the eye is in approximately midstroke, but in this position the roll 88 is backed off from the weaving point, thereby increasing the length of thread necessary to extend from the stud 89 to the eye by an amount exactly equal to the decrease in the distance from the eye to the weaving point. That is, as the eye is moved so as to decrease its distance from the weaving point, the roll 88 is moved outward, and as such distance is increased, the roll 88 is moved inwardly, thereby correspondingly increasing and decreasing the distance from the stud 89 around the roll 88 and to the eye by equivalent amounts. Thus, the stud is a fixed guiding point or ledge, about which the thread is bent, and the link 51 is a take-up connected to the heddle at one end, while its opposite end carries a thread guide (roll 88) which is constrained by the link 50 to move in and out from the weaving point, taking up and paying out the slack of the warp thread.

I will now describe the modification in the heddle construction and the associated warp thread take-up mechanism illustrated in Figs. 9 to 12. In this modification the slides or heddles themselves are essentially the same as those already described, and are identified by the same reference characters. As before 34 and 35 represent adjacent heddles or slides, which are exactly alike in construction and differ only in position, 34 denoting the slides which are elevated and 35 those which are depressed. The new construction embodied in this modification involves mainly two additional eyes 781 for warp threads, which are connected to each heddle. The additional eyes connected with the heddle 34 are formed as holes in the ends of rods 342 and 343 which rise from the top of the heddle and are bent over approximately in mid length. The corresponding eyes of the heddle 35 are formed similarly in the ends of rods 352 and 353 having similar form and being similarly arranged with respect to the heddle 35. These rods are so arranged that the additional eyes 781 lie upon opposite sides and at the same level with the eye 78 of the heddle, which is formed, arranged, and located substantially as already described. The rods in which these eyes are formed are given the peculiar shape shown in order that their offset portions or bends 345 and 355, respectively, will not interfere with the upper ends of the guides 73 between the adjacent heddles. These rods may be described as extending upwardly in the spaces between the guides wherein the heddles are placed, and bent over on a bend of such radius that the downwardly extending parts of the rods extend approximately midway between the adjacent

heddles. These bends are at such a height that they lie slightly above the upper ends of the guides when the heddles are in their most depressed condition, as indicated in Fig. 10 with respect to the rods on the heddle 35. Each additional eye lies farther away from the heddle to which it is connected than from the adjacent heddle, whereby all of the warp threads controlled by each heddle are arranged in alternation with the warp threads controlled by the adjacent heddles. Thus, referring to Fig. 11, which shows the warp threads diagrammatically, the lines *a*, *b*, and *c* represent the warp threads controlled by the left hand heddle shown; *d*, *e*, and *f* represent those controlled by the intermediate heddle and *g*, *h*, and *i* those controlled by the right hand heddle shown. Thus assuming that the middle heddle is depressed and the other two are raised, then it will be apparent that the warp threads *b*, *c*, *g* and *h* are raised while *d*, *e*, and *f* are depressed; that is, that every other warp thread is raised while the intermediate threads are depressed, which is the condition required for weaving.

The downwardly extending portions of these rods are contained in longitudinal passages 732 in the upper ends of the guides and are exposed in slots 733 passing through said guides from the outer to the inner sides thereof and being enough longer than the travel of the heddles to give free course for the warp threads in all positions of the eyes 781. The ends of the rods are beveled as shown in Fig. 10 so as to push aside and pass by the warp threads carried by the adjacent rods, without interference.

The improvement last described enables a much greater number of warp threads to be woven, and thereby a structure of finer mesh to be produced, without increasing the size of the loom; that is from two to three times as many warp threads may be woven in a loom having the triple eye heddles as in a loom of the same size having single eye heddles. This improvement makes possible the production of finer and more closely woven tubular fabrics and at a less expense than has heretofore been possible. Of course it is to be understood that this feature of the invention is not limited to any particular number of additional eyes associated with the heddle. I have here shown with each heddle three eyes, for that is a convenient arrangement, and I may make heddles with two eyes, or more than three, and the protection which I claim for this feature of the invention is intended to cover any construction in which the heddle has two or more eyes arranged in alternation with the eyes of the adjacent heddles, arranged for circular weaving.

Essentially the same warp take-up mechanism as heretofore described is shown in

connection with the modified heddle construction, but embodying modifications in the way of additional guide rolls or guides for the various warp threads. That is, whereas each take-up comprises links 50 and 51, substantially as hereinbefore described, the links 50 carry at each side thereof brackets 501, 502, each equipped with a guide for an additional warp thread and so arranged that the bracket arm 501 carried by one link 50 crosses the bracket 502 carried by the adjacent link 51, as shown in Fig. 12, whereby the adjacent guide rolls travel oppositely to one another. Each take-up motion thus carries three guide rolls 88, or a number of guide rolls equal to the number of eyes of the heddle.

Each warp thread may also control or operate a stop motion of substantially the character, as shown in Fig. 9, where part of one such stop motion is shown and designated by the reference characters used in Fig. 3.

A stop motion controlled by the breakage of the warp is here shown in part, but is not described or claimed herein, as it forms the subject of a divisional specification containing matter divided from the present specification.

I have illustrated in Fig. 14, a form of clutching device operable by the shipping lever 127 for connecting the power drive with the machine. This figure shows the loose pulley 43 and the clutch disk 44 upon the main shaft 42. The shipper lever is connected by means of a link or connecting rod 198 (Fig. 2) with a bell crank having a hub 199 which turns upon a fixed stud 200 and having also an arm 201 with a cam projection 202. The latter bears on a lever 203 which is pivoted on a fixed pivot 204 and engages a sleeve 205 which slides loosely on the shaft 42 in a well known manner. This sleeve is connected by means of links 206 with levers 207 pivoted by pins 208 to the hub of the pulley and having short arms bearing against an abutment 209 which is a collar loose on the shaft but limited as to its movement away from the pulley by an adjustable nut 210 which is threaded on the shaft. The adjacent faces of the pulley 43 and clutch disk 44 are provided with faces 211 of leather or other friction producing material. In the position shown in Fig. 14 the clutch is connected.

I contemplate modifying in various ways the mechanisms here shown, for example the warp take-up devices; therefore I do not limit my claim for protection to the precise forms and constructions here shown. In regard particularly to the warp take-up mechanisms shown in Fig. 3, I do not limit myself to the links 50, or exclude the use of other means than such links for support.

ing and guiding the rolls 88, or equivalent thread guides, in a manner such as to secure the main object sought.

It is of course to be understood that the descriptive language used in the foregoing specification and in the following claims to indicate direction and relation such as "up," "down," "high," "low," "above," "below," "vertical," "horizontal," and words of analogous import are not intended to be limitations of the invention, but are used simply for convenience of description as applied to the particular constructions shown, and are to be construed with a broader meaning than indicated by their literal definitions; that is, so as to apply to any loom, and the parts thereof which have essentially the coöperative relation and mode of operation here described, whether in the particular relation to the horizon here shown or not.

In the foregoing specification I have described the entire loom in order to explain all of the coöperating component parts of an organized practical machine, including therein certain constructions and features which are not my original invention, but are the inventions of other parties for which protection is sought in other applications. The features which I consider to be my original invention and which I desire to protect therein are particularly pointed out in the following claims.

What I claim and desire to secure by Letters Patent is:

1. In a circular loom the combination with a plurality of parallel guides arranged concentrically about an axis, sliding heddles mounted between and in engagement with said guides, cylindrical cams concentrically arranged with an annular space between them for operating said heddles, the heddles and the ends of said slides extending into such annular space, and a ring engaged with the inner ends of said guides, said ring having notches or recesses into which the ends of said guides pass, and by which such ends are restrained from deflection.

2. A circular loom comprising a rigid frame, concentrically arranged rotatable cams having an annular space between them, guide bars mounted on said frame projecting into such annular space, heddles engaged and guided by said bars and also engaged for operation by said cams, and a steady ring within such annular space adjacent to the ends of said bars, having notches receiving said bars and retaining the latter from deflection.

3. In a circular loom, a plurality of reciprocating heddles or slides, means for moving adjacent heddles back and forth in relatively opposite directions, and an additional thread guiding eye carried by each heddle at the side thereof toward the ad-

jacent heddle so arranged that each such additional eye is between the threads controlled by the additional eye of the adjacent heddle and by the heddle itself.

4. In a circular loom, a plurality of reciprocating heddles, means for moving said heddles in such manner that adjacent heddles always travel oppositely to one another, each heddle having a plurality of warp guiding eyes so arranged that each warp thread controlled by one heddle is between the warp threads controlled by the two adjacent eyes of the next heddle.

5. In a circular loom, a series of parallel guides having spaces between them, sliding heddles arranged in such spaces, a rod projecting from each heddle in the direction of movement of the heddle, being doubled back at a distance from the heddle greater than the extent of movement thereof plus the extent which the adjacent guide projects beyond the end of the heddle when the latter is in the position nearest to such end of the guide, to form a backwardly projecting part, such backwardly projecting part having an eye and the heddle itself having an eye, and the rod being so disposed that such backwardly projecting part lies between the heddle carrying the rod and the adjacent heddle, and its eye is between the adjacent heddle and the eye carried by the similar rod which is mounted upon said adjacent heddle.

6. In a circular loom, a series of guides having guideways between them, a heddle or slide mounted to reciprocate in each of said guideways, and each guide having a channel between the guideways arranged to admit warp threads and being longer than the extent of travel of the heddles, rods carried by each heddle extending to either side thereof having their ends lying in such channels and being offset between their ends in the direction of travel of the heddles a distance sufficient to clear the end of the guide, that portion of each of said rods so contained in said channel having an eye for guiding a warp thread and being arranged so that each of said eyes passes between the adjacent heddle and the eye of the rod carried by such adjacent heddle.

7. In a circular loom, a plurality of oppositely reciprocating heddles or slides arranged in a circular series to travel in parallel paths, each heddle having an eye, a rod mounted upon each heddle having an eye in its extremity, the rods of adjacent heddles crossing one another whereby each of the eyes associated with either heddle is between two eyes associated with the adjacent heddle, and said rods being offset between their ends in the direction of movement of the heddles whereby to clear the warp threads and the heddle guiding means.

8. In a circular loom the combination of

- a fixed guide with heddles on each side of said guide, each of said heddles having a warp receiving eye, the guide having a passage intermediate the heddles through which 5 warp threads may pass to the weaving point, and rods secured to each heddle having their ends contained in such passage and being offset between their ends to clear the end of the guide, each of said rods having in 10 such end a warp receiving eye which is located between the eye of the other heddle and the eye of the rod carried by said other heddle.
9. In a circular loom, a plurality of oppositely reciprocating heddles and means for moving adjacent heddles oppositely to one another, each heddle having three or more eyes with parts carrying said eyes so constructed and arranged that each eye of each 15 heddle is arranged between two eyes of adjacent heddles.
10. In a circular loom the combination with reciprocating heddles each having a plurality of eyes for warp threads, the eyes 20 of adjacent heddles being in alternating arrangement and moving in relatively opposite directions, and warp thread take-up linkages associated with each heddle, each of said linkages comprising two links pivoted together and one of said links connected 25 to the heddle and the other mounted upon a fixed pivot, a guide for the thread carried at the knuckle of each linkage, and brackets having thread guides mounted at each side 30 of the knuckle, the brackets of adjacent linkages passing one another.
11. In a circular loom in combination with heddles each having a plurality of eyes arranged in alternation with one another, a 35 warp thread take-up associated with each heddle, each take-up comprising a link pivoted on a fixed pivot and a second link pivoted to the first link and connected to the heddle, the first named link of each heddle 40 having a bracket on the side thereof toward the link of the adjacent take-up, and the brackets thus extending being carried past one another.
12. A warp thread take-up for a circular 45 loom having multiple eyed heddles comprising a series of links arranged side by side to oscillate upon fixed pivots, brackets on each of said links extending toward the adjacent links, and the oppositely extending brackets of adjacent links passing beyond 50 one another, thread guiding means carried by said brackets, and a link connecting each of the above described links with the adjacent heddle.
13. In a circular loom a series of heddles 55 each having a thread-bearing eye and reciprocatively mounted to carry said eye back and forth across the plane of weaving, and a warp thread take-up means comprising a link connected to each heddle and extending 60 therefrom away from the weaving point, a support for the outer end of the link arranged to compel such end to move toward and away from the weaving point with the travel of the heddle, a warp thread guide 65 connected to said link and moving therewith, and fixed guides at different heights with respect to the weaving plane and at different distances from the first named 70 guide, the warp thread in passing through 75 the first named guide being led across the inner side of the fixed guide which is more remote, and around the outer side of the fixed guide which is nearer, to the first named guide.
14. In a circular loom the combination with a reciprocating heddle bar having a warp thread eye, of a link pivoted to the heddle bar at a point near the eye, a second link pivoted on a fixed pivot at the side of 80 the heddle away from the weaving point, said links being jointed together, a warp thread guide at the joint between the links and being caused to move toward and away 85 from the weaving point as the heddle reciprocates, and two fixed guides between which the warp thread is led in passing to the first-named guide, said fixed guides being arranged to bend the warp thread alternately when the guide which is carried by 90 the links is at the opposite extremities of its back and forth movement.
- In testimony whereof I have affixed my signature.
- JOSEPH A. KENNEDY.
